(57) **CLAIM**

The ornamental design for a powered prosthetic knee, as shown and described.

DESCRIPTION

FIG. 1 is a front elevational view of a powered prosthetic knee showing our new design;

FIG. 2 is a rear elevational view thereof;

FIG. 3 is a right side elevational view thereof;

FIG. 4 is a left side elevational view thereof;

FIG. 5 is a bottom plan view thereof;

FIG. 6 is a top plan view thereof;

FIG. 7 is a front perspective view thereof;

FIG. 8 is a rear perspective view thereof;

FIG. 9 is a front elevational view thereof, with the cover being removed;

FIG. 10 is a rear elevational view thereof, with the cover being removed;

FIG. 11 is a right side elevational view thereof, with the cover being removed;

FIG. 12 is a left side elevational view thereof, with the cover being removed;

FIG. 13 is a top plan view thereof, with the cover being removed;

FIG. 14 is a bottom plan view thereof, with the cover being removed;

FIG. 15 is a front perspective view thereof, with the cover being removed; and,

FIG. 16 is a rear perspective view thereof, with the cover being removed.
